BIRDHOUSE

William P. Kupka, Chelsea, Iowa

Application April 27, 1954, Serial No. 30,211

Term of patent 3½ years

(Cl. D31—2)

To all whom it may concern:

Be it known that I, William P. Kupka, a citizen of the United States, residing at Chelsea, in the county of Tama and State of Iowa, have invented a new, original, and ornamental Design for a Birdhouse, of which the following is a specification, reference being had to the accompanying drawings, forming a part thereof.

Fig. 1 is a front view of a birdhouse showing my new design,

Fig. 2 is a side view of this birdhouse,

Fig. 3 is a side view opposite to that in Fig. 2, and

Fig. 4 is a bottom view thereof.

I claim:

The ornamental design for a birdhouse, as shown.
